Inventor,
Charles Henry Allen

By: Nicolas E. Bellows

Attorney.

UNITED STATES PATENT OFFICE.

CHARLES HENRY ALLEN, OF ATTLEBORO, MASSACHUSETTS.

FASTENING DEVICE.

1,212,308.

Specification of Letters Patent. Patented Jan. 16, 1917.

Application filed March 6, 1916. Serial No. 82,380.

To all whom it may concern:

Be it known that I, CHARLES HENRY ALLEN, a citizen of the United States, residing at Attleboro, in the county of Bristol and State of Massachusetts, have invented certain new and useful Improvements in Fastening Devices, of which the following is a specification.

My invention relates to fastening devices for different purposes such for instance as cuff buttons of the link type.

The essential objects of my invention are to enable the article to which it is attached to be moved some distance without removing the fastening device therefrom; to conceal the spring element and render the structure pleasing to the eye; and to cheapen the expense of construction; and to attain these ends in a structure which is easy to manipulate.

To the above ends essentially my invention consists in such parts and combinations of parts as fall within the scope of the appended claims.

In the accompanying drawings which form a part of this specification, Figure 1 is a side elevation of the complete button, Fig. 2, a similar elevation, showing the connecting members at a different angle, Fig. 3, a longitudinal section of the device, Fig. 4, a detail view of the slidable link member with the spring located therein, Fig. 5, a detail view of the housing link member, Fig. 6, a section on line 6—6 of Fig. 1. Fig. 7 is a detail showing the interlocking of the lips of the housing.

Like reference characters indicate like parts throughout the views.

In the drawings 1 represents the button heads of any usual preferred construction comprising in the present instance outer shells 2 and linings 3 engaged in the outer shells by downwardly bent flanges 4 and integral with which are central loops 5 adapted to engage the ends of the connecting member.

The central member comprises a housing link 6 shown in detail in Fig. 5 comprising

parallel shells 7 spaced from each other, but connected at one end by an integral post 8 and at the other end by interlocked lips 9', 9'' which when overlapped as seen in Fig. 7 form a post 10. This complete housing link has side openings 11 and one of its posts such as 10 engages one of the loops 5. Inside this link is a helical spring 12 abutting at one end against the post 8 and at its other end pressing against one end of a link 13 which also incloses the spring and whose other end passes through the second loop 5, the link sliding in the openings 11. This compound connecting member it will be observed is capable of expansion by any drawing action upon the button heads 1, whereby the link portions 6 and 13 slide relatively to each other and compress the spring 12. The spring returns the heads to normal position after the drawing influences upon the heads are discontinued.

I claim:

1. An extensible fastening device for soft cuffs and the like, comprising heads with loops upon their adjacent faces, relatively slidably interengaging links each having an end passed through one of said loops, said links being guided one upon the other, and resilient means in the links for restraining the same against movement in opposite directions, the same forming a compound flexible connecting member.

2. An extensible fastening device for soft cuffs and the like, comprising heads with loops upon their adjacent faces, relatively slidably interengaging links each having an end passed through one of said loops, said links being guided one upon the other, and resilient means in the links for restraining the same against movement in opposite directions, the same forming a compound flexible connecting member, the loops of the heads and the connecting member extending in the same plane to facilitate insertion in the buttonholes of the cuff.

3. A fastening device of the character designated, comprising heads having loops, a housing link composed of parallel shells

spaced from each other with a connecting loop at one end and interlocked loops at the other end forming a post, said housing having side openings, a link slideable in said 5 openings, one end of said housing being connected with one of said loops and one end of said link with the other loop, and a spring

inclosed by said housing and link and abutting at one end against a post of the housing and at the other end against one end of 10 the said link.

In testimony whereof I have affixed my signature.

CHARLES HENRY ALLEN.
